UNITED STATES PATENT OFFICE

2,549,502

SHOE STRETCHER

Roy F. McClenathan, Moorheadville, Pa.

Application March 3, 1950, Serial No. 147,425

3 Claims. (Cl. 12—128.5)

1

The device of the present invention consists of a shoe stretcher, the principal object of the invention being to provide a stretcher capable of selective expansion of the vamp of a shoe at the toe, ball or uniformly from toe to ball.

A further object of the invention is to provide a shoe stretcher which, when it is desired to stretch the shoe from toe to ball, will automatically adjust itself to exert equal pressure on all portions of the vamp.

It is also within the contemplation of this invention to provide a wholly articulate stretcher responsive to a pushing, pulling and rotating action of an operating shaft completely within the control of the user to effect expansion of either the fore or aft parts of the stretcher heads or uniform lateral displacement, when desired, while the stretcher is mounted within the shoe.

A still further object of the invention is to provide a shoe stretcher durable in structure and requiring a minimum amount of effort to effect the expansion.

Other objects will be apparent from the following description of the present preferred form of the invention wherein:

Figure 1 is a top plan view of a shoe stretcher in position to effect uniform expansion of the shoe frame, from toe to ball, constructed in accordance with the present invention, parts being broken away to disclose details;

Figure 2 is a similar view with a part of the operating shaft broken away and the stretcher heads intact, illustrating the position of the heads when used to stretch the toe portion of the vamp;

Figure 3 is a similar view illustrating the position of the stretcher heads when used to stretch the ball portion of the vamp;

Figure 4 is a transverse sectional view taken along the lines 4—4 of Figure 4, looking in the direction of the arrows and showing to advantage the manner of mounting the spring in the stretcher heads; and

Figure 5 is a transverse sectional view taken along the line 5—5 of Figure 1, looking in the direction of the arrows, showing the manner of engaging the aft bearing with the operating shaft and the stretcher heads.

The assembly A includes yieldably engaged parallel heads 6 each of which tapers to a point at the fore end, as indicated at 7, the aft end of each head being abrupt and provided with lugs 8. The inner wall of each head is recessed as indicated at 9 and curved at a point adjacent the toe of the head to provide an arcuate surface 9'. The rear end of each recess 9 is formed to provide a

2

guideway 10. The central portion of each head is cored out, as shown in Figure 4, to provide a housing 11 for an endless helical spring 12 which normally urges the proximate face 13 of heads 6 into engagement. By using only the one spring, the force exerted is equally distributed along the entire length of the spring and correspondingly equally exerted on the heads 6 on both sides of the shaft.

10 The expander assembly B includes a shaft 14 provided at one end with a handle 15, equipped near its other end with a worm thread 16. The portion of the shaft beyond said thread is reduced as indicated at 17. The shaft 14 carries fore, intermediate and aft spreaders 18, 19 and guide bearing 20, respectively. The spreader 18 serves as an expander and is mounted on said reduced end 17 of the shaft, in a manner more fully hereinafter described. The spreader 19 is also an expander and is threaded on the worm thread 16 and the guide bearing 20 is slidably mounted on the shaft 14 aft of the thread 16. The spreaders 18 and 19 are mounted within the heads A and the guide bearing 20 aft of the latter.

25 Spreader 18 is convexly curved as indicated at 21 to complement the concave contour of curved inner wall 9' of each head 6. The foremost portion of spreader 18 tapers to a point as at 22 so that the spreader is wholly within stretcher heads A and disposed contiguous with recessed inner wall 9. The central portion of spreader 18 is cut out as indicated at 23 to receive a collar 24 which is keyed to shaft 14 as denoted at 25. This collar exerts on spreader 18 a force capable of producing a longitudinal displacement thereof. Adjacent cut-out 23 is a recess 26 in which is a ball bearing 27. Reduced shaft 17 extends through collar 24 into recess 26 where it engages ball bearing 27 to form a thrust bearing. This thrust bearing greatly reduces the amount of effort required to rotate shaft 14 and expand the heads A.

30 The spreader 19 is hexagonal and threaded on worm thread 16 and moves relatively to spreader 18 only when shaft 14 is rotated. Two adjacent sides of the spreader 19 are tapered as indicated at 28 to complement guideways 10. The spreader 19 is hexagonal and threaded on worm thread 16 and moves relatively to spreader 18 only when shaft 14 is rotated. Two adjacent sides of the spreader 19 are tapered as indicated at 28 to complement guideways 10.

35 Guide bearing 20 is slidably mounted on shaft 14 aft of stretcher heads A. Lateral extensions of guide bearing 20 form parallel bearing plates 29, to each of which is pivotally secured one end of a link 30. The other end of link 30 is similarly engaged with lugs 8 aft of stretcher heads A, as shown to advantage in Figure 5, to produce an articulate movement. This articulation produces a relative movement

of spreader 20 with respect both to the shaft 14 and stretcher heads A. The sliding movement of spreader 20 determines the relative position of the stretcher heads A with respect to each other.

In use the stretcher is placed within the shoe and handle 15 is rotated clockwise until stretcher heads A frictionally engage the vamp from toe to ball. Movable guide bearing 20 automatically adjusts the stretcher to produce equal pressure at all points of the vamp. If then, it is desired to uniformly stretch the vamp, handle 15 is further rotated until the desired expansion is attained. Guide bearing 20 at all times equalizes the pressure on the vamp.

To stretch the toe, after frictional engagement of the stretcher heads A and the vamp, the handle 15 is rotated and a push exerted on it. This urges spreader 19 against the wall of cored out housing 11 and causes spreader 18 to slide toward along curved walls 9'. As a result the stretcher heads A converge at the ball, diverge at the toe and guide bearing 20 slides on shaft 14 relatively to the movement of the heads. Figure 2 is illustrative of this operation.

The same general procedure is followed in stretching the ball portion with the exception that a pull instead of a push is exerted on the handle 15. Spreaders 18 and 19 slide along arcuate surface 9' and guideway 10, respectively, toward the aft end of stretcher heads A causing convergence of the heads at the toe, divergence at the ball and movement of guide bearing 20 relatively thereto. This operation is shown advantageously by Figure 3.

While the invention has been described in detail in its presently preferred embodiment, it will, of course, be understood that such has been done for purposes of illustration only and not by way of limitation, and therefore only such limitations are to be imposed thereon as may reasonably come within the scope of the appended claims.

I claim:

1. A shoe stretcher including yieldably engaged parallel heads, an expander assembly for

the heads comprising a shaft and multiple spreaders carried by the latter, one of the spreaders being mounted on the forward end of the shaft within the heads, another spreader being within the head through which the shaft is threaded, a guide bearing being movably mounted on the shaft and movably engaged with the aft ends of the heads, the spreaders and shaft being constructed and arranged to effect selective uniform lateral movement of the heads and relative movement of the fore parts of the heads and relative movement of the aft parts of the heads, by manual manipulation of the shaft when the stretcher is mounted in a shoe.

2. A shoe stretcher including yieldably engaged parallel heads, and an expander assembly for the heads comprising a shaft one end of which is mounted within the heads and equipped with a spreader, a thrust bearing for the shaft mounted in the spreader, and a guide bearing slidably mounted on the shaft and engaged with the stretcher heads to permit fore and aft movements of the shaft with respect to the stretcher heads.

3. A shoe stretcher to effect independent expansion of the toe and ball of the shoe to effect uniform expansion of the fore part of a shoe from the toe to the ball including parallel engaged heads, a handle one end of which is screw-threaded and engaged between said heads, a pair of spreaders mounted with said heads, one of the spreaders being engaged with said handle, and a guide bearing slidably mounted on said handle and in pivotal engagement with said heads.
